UNITED STATES PATENT OFFICE.

HERBERT S. MILLS, OF CHICAGO, ILLINOIS.

COIN-OPERATED WEIGHING-SCALE.

1,139,993.

Patented May 18, 1915.

Application filed December 1, 1914. Serial No. 874,992.

To all whom it may concern:

Be it known that I, HERBERT S. MILLS, a citizen of the United States, residing at Chicago, in the county of Cook and State of Illinois, have invented a new and useful Improvement in Coin-Operated Weighing-Scales, of which the following is a specification.

My invention relates to an improvement in the class of coin-operated weighing-scales, in which the scale beam is normally locked against proper balancing until released upon the insertion of a suitable coin or token.

The primary object of my invention is to guard against repeated use of the scale by different persons or bodies, for showing the weight of each, without inserting a coin for each use, by timing, through the medium of simple mechanism, the released condition of the beam to a period only about sufficient to enable it to be balanced for ascertaining the weight of one such imposition on the scale-platform.

Preferred mechanism for accomplishing this purpose is illustrated in the accompanying drawings, in which—

Figure 1 is a broken view showing, in front elevation, the upper part of a scale of the Fairbanks type, in which mechanism embodying my invention is contained; Fig. 2 is a similar view with a portion of the front plate broken away to disclose the beam-operating lever mechanism and the locking member of my improvement; Fig. 3 is a broken view presenting the inner side of the head face-plate carrying the mechanism embodying my invention and shown in elevation in the normal beam-locking position; Fig. 4 is a broken and partly sectional view showing the coin-chute and a coin which has passed therethrough into position to render the timing mechanism operative; Fig. 5 is a section on line 5, Fig. 4; Fig. 6 is a broken view of the showing in Fig. 3, but presenting parts in the positions to which they have been brought by turning the operating lever nearly to its full extent of depression, and Fig. 7 is a view like that presented in Fig. 3, but showing the parts in the positions they occupy after releasing the operating handle to effect release of the inserted coin and actuate the timing mechanism.

The scale in connection with which my invention is illustrated is of known general construction, involving a spring-platform (not shown), from the rear end of which

rises a hollow post 8 (Fig. 1) carrying a head 9. The head, in the present instance, is hollow and provided with a face-plate 10 equipped with a lock, indicated at 11, for releasably securing the plate in its head-closing position. On the head is supported the scale-beam 12, as usual in the present type of scale; and a rod 13 connects the spring-platform with the beam-actuating lever 14, which has a link-connection at 15 with the scale-beam near its fulcrumed end.

A coin-insertion slot is provided at 16 in the top of the head 9. The mechanism hereinafter described is all preferably supported by being secured to the inner face of the plate.

A curved coin-chute 17, registering at its upper end with the adjacent end of the insertion-slot, contains a transverse opening 18 near its lower end to admit a stop-finger 19^a projecting from a spring-pressed arm 19 pivoted on the chute, and the purpose of which is to hold back a second coin that may be introduced into the chute until the first has been discharged therefrom and has served its purpose in enabling the timing mechanism to be operated, and until the machine is again worked as hereinafter explained. A projection shown as a stud 20 extends from the beam-controlling lever-member 14 into the path of the hooked end of a bent or bell-crank-species of spring-pressed lever 21 fastened between its ends on the arbor of a ratchet 22^a in an incased train of gears 22. This arbor carries, loosely, the first gear of the train, and a spring-pressed pawl 23 is pivotally supported on that gear to drive the train by turning the ratchet in one direction, but to slide over the ratchet-teeth by turning the ratchet in the contrary direction. A brake-fan 24 is secured on the arbor of the last pinion in the train to prolong and thus time its running down, as and for the purpose herein-after explained.

An operating handle 25 (Fig. 1) is secured on a stub 26 journaled in the face-plate 10 and carrying on its inner end a spring-retracted lever 27 provided on its forward end with a rectangular finger 27^a. Another spring-retracted lever 28, fulcrumed just above the fulcrum of the lever 27, terminates at its forward end in a longitudinally slotted head 29 containing a seat 30 for a coin and through the slot in which the finger 27^a projects to overhang the coin-

seat. On one side of the head 29 is pivoted a spring-retracted tongue 29^a, into the path of which the longer arm of the bent lever 21 extends. A ratchet-toothed curved bar 31, pivoted at its lower end, has its opposite end spring-held in position to tend to extend the teeth on the bar into the path of a projection 32 on the forward end of the lever 27.

In the normal condition of the scale, the hooked end of the bent lever 21 engages the stud 20 on the beam-lever 14 to prevent a body imposed on the scale-platform from balancing the scale-beam, by shifting the weights shown thereon, with any degree of accuracy. In that condition of the scale, depression of the operating handle 25 will turn the lever downwardly without affecting the locked condition of the scale-beam lever, since the finger 27^a will pass down freely through the slot in the head 29 and fail to move the lever 28, which must move with the lever 27 to effect the unlocking. A person using the scale to cause the latter to indicate his weight, mounts the scale-platform, and upon inserting a coin into the slot 16 the coin passes through the chute and lodges on its seat in the head 29. Upon then depressing the operating handle to throw the lever 27 downwardly, the finger 27^a encounters the coin in its path and, through that medium, depresses the lever 28, the finger thereby clamping the coin on its seat. In the downward movement of the two levers the projection 32 slides over the teeth of the bar 31, but they prevent the return of the two levers to normal position until the ratchet-bar is forced backwardly, as hereinafter described. In the downward throw of the levers 27 and 28 the tongue 29^a, by yielding in that movement, clears the end, in its path, of the longer arm of the bent lever 21. The lever 27 is shown in Fig. 6 at the lowermost end of its throw, in reaching which, being fulcrumed on a different center from that of fulcruming the companion lever 28, the edge of the vertical portion of the angular finger 27^a, in describing a different arc from that described by the adjacent end of the lever 28, pushes the coin out of the head 29, and the coin drops through a hopper 33 into a suitable coin-receptacle (not shown) in the post 8. This dislodgment of the coin frees the lever 28, permitting it to be turned back toward normal position by the recoil of its controlling spring. In this turning, the tongue encounters the bent lever 21 and turns the latter to drive the train of gears 22, but at a speed more retarded than the force of the lever spring would produce, because of the braking action of the fan 24 in overcoming atmospheric resistance. When the tongue first begins to turn the lever 21, it trips the hooked end of the latter out of engagement with the stud 20, thereby unlocking the lever 14 and permitting the

scale-beam to be properly balanced, by shifting the weights thereon, to accurately show the weight of the body on the scale-platform. When, in the continued return-movement of the lever 28, the tongue clears the adjacent end of the lever 21, a spring 21^a retracts the latter to engage its hooked end with the stud 20 to again lock the lever 14 and impair the balancing function of the scale-beam. The braking action of the fan 75 retards the upward movement of the lever 28 to maintain the scale in normal working condition for a period only sufficiently long to enable the weighing operation, for which the coin is inserted, to be performed. Just before the lever 28 reaches the end of its upward throw, the forward end, at 34, of one side of the head 29, which is slightly longer than the opposite side, encounters the upper curved part of the bar 31 extending into its path, and forces the bar against the resistance of its retracting spring in the direction to take the teeth on the bar out of the path of the projection 32, whereupon the spring controlling the lever 27 quickly retracts the latter to its normal position represented in Fig. 1, thereby completely restoring the scale to its normally inoperative condition in which it is ready to be again operated in the manner described.

I realize that considerable variation is possible in the details of construction thus specifically shown and described, and I do not intend by illustrating a single specific, or preferred embodiment of my invention to be limited thereto; my intention being, in the following claims, to claim protection upon all the novelty there may be in my invention as broadly as the state of the art will permit.

What I claim as new and desire to secure by Letters Patent is—

1. In a weighing-scale, a poising scale-beam, a spring-retracted lever for locking the beam against accurate balancing, spring-retracted lever-mechanism rendered operable by the insertion of a coin to trip said lever and unlock the beam, and retarding means connected with said lever for timing the return thereof, under the retractive force of its spring, to normal locking position.

2. In a weighing-scale, a poising scale-beam, timing-means comprising a train of gears and a fan-brake on an arbor of said train, a spring-retracted lever on another arbor of said train, for locking the beam against accurate balancing, and spring-retracted lever-mechanism rendered operable by the insertion of a coin to trip said lever and unlock the beam.

3. In a weighing-scale, a poising scale-beam and an operating lever therefor provided with a projection, timing-means comprising a train of gears and a fan-brake on an arbor of said train, a spring-retracted

lever on another arbor of said train normally engaging said projection to lock the beam against accurate balancing, and spring-retracted lever-mechanism rendered operable 5 by the insertion of a coin to trip said lever out of engagement with said projection.

4. In a weighing-scale, a poising scale-beam and an operating lever therefor provided with a projection, a spring-retracted lever having a hook normally engaging said projection to lock the beam against accurate balancing, spring-retracted lever-mechanism rendered operable by the insertion of a coin 10 to trip said lever out of engagement with said projection, and retarding means connected with said lever for timing the return thereof under the retractive force of its spring to normal locking position.

5. In a weighing-scale, a poising scale-beam and an operating lever therefor provided with a projection, timing-means comprising a train of gears and a fan-brake on an arbor of said train, a spring-retracted lever on another arbor of said train, having a hook on one end normally engaging said projection to lock the beam against accurate balancing, spring-retracted lever-mechanism rendered operable by the insertion of a coin 20 to trip said lever, said mechanism comprising a lever fulcrumed on one center and provided on one end with a bent finger, a second lever fulcrumed on another center and terminating in a slotted coin-seating head through which said finger normally projects, and a 25 spring to normal locking position.

30

35

said locking lever normally projects, an operating handle connected with said finger-carrying lever, and spring-held means for retaining said last-named lever in its downwardly-thrown position until released by said headed lever in regaining its normal position.

6. In a weighing-scale, a poising scale-beam, a spring-retracted lever normally locking the beam against accurate balancing, spring-retracted lever-mechanism rendered operable by the insertion of a coin to trip said lever and release the beam, said mechanism comprising a lever fulcrumed on 40 one center and provided on one end with a bent finger and a projection, a second lever fulcrumed on another center and terminating in a slotted coin-seating head through which said finger normally projects, and a 45 spring to normal locking position.
